UNITED STATES PATENT OFFICE.

RALPH DOWNEY PRITTLE, OF CALGARY, ALBERTA, CANADA, ASSIGNOR TO JAMES H. DIXON, OF CALGARY, ALBERTA, CANADA.

METHOD OF TREATING WOODEN POLES AND THE LIKE.

Application filed February 28, 1923. Serial No. 621,951.

This invention relates to a process and apparatus for treating with the same kind or two different kinds of liquid preservatives, wooden telegraph and telephone poles, 5 piling, posts and similar pieces or sticks of wood, so as to treat one end of the pole which is let into the ground with a heavy and strong liquid preservative and the opposite end of the same which is above ground 10 with a light and weak liquid preservative and thus treat the different parts of the same in accordance with the exposure to decay of the respective parts.

The object of this invention is to provide 15 a method and apparatus whereby wooden poles may be treated with liquid preservatives of different strength at opposite ends thereof efficiently, economically and expeditiously and insure a product which is dependable and of uniform quality.

In the accompanying drawings:

Figure 1 is a diagrammatic sectional elevation of an apparatus containing my improvements and suitable for practicing this 25 method. Figure 2 is a fragmentary sectional elevation showing a preferred means for handling the poles in groups or bundles. Figure 3 is a vertical section showing a 30 modified arrangement of the impregnating tank.

Similar characters of reference refer to like parts throughout the several views.

A suitable apparatus embodying my invention and adapted for practicing my improved method is shown in Fig. 1 and constructed as follows:

1 represents an upright treating or impregnating tank or chamber which is adapted to receive in a vertical position the poles, 40 piles, posts 2 or the like, to be treated with a heavy or strong liquid preservative, this tank being preferably sufficiently large in diameter to receive a plurality of such poles, which are arranged side by side in a group.

100 represents an upright treating or impregnating tank or chamber which is adapted to receive, in an upright position the poles, piles, posts 2, or the like, to be treated with a light or weak liquid preservative, this tank being also sufficiently large in diameter to receive a group or bundle of such poles.

In its preferred form, each of these tanks comprises an upright cylindrical body or wall 3, a flat bottom 4 which is secured to the lower end of the wall, and a movable

top or cover 5 which is preferably pivoted at one part of its edge by means of a hinge 6 to an upper edge portion of the side wall and adapted to be clamped against the upper end of this wall by means of bolts 7 or similar means, so that the tank may be hermetically sealed during the operation of treating a group of wooden poles therein. Each of these tanks is preferably constructed of sheet metal and is of sufficient height to take in 60 wooden poles of normal or commercial lengths. Tanks having a height of about forty feet and a diameter of about eight feet will be found at present to answer all practical purposes. These tanks or vats may 65 either rest with their lower ends upon the surface of the earth or this same may be let into the ground more or less to suit conditions or requirements. For the purpose of permitting the operators to manipulate the 70 covers or lids at the top of the impregnating tanks for opening and closing the same, a platform or gallery 8 is preferably mounted around the upper parts of the tanks and an upright ladder 9 is arranged at one side wall 75 of the same for the purpose of enabling the attendants to easily reach the gallery or platform from the ground.

Various preservatives may be employed 80 for treating the wooden poles heavily and strongly, for instance, liquid creosote having a strong, high, or powerful protective capacity may be employed for treating the butt ends of poles which are let into the ground 85 and liquid zinc-chloride may be employed for treating those parts of the top portions of the poles which are arranged above the ground when in use and not subject to as great a decay as that part of the pole which 90 comes in contact with the ground.

A supply of liquid creosote may be obtained from any suitable source but preferably from a reservoir 10 from which the creosote is drawn into the lower part of the creosote impregnating or treating tank or 95 vat and to which the unused part of the creosote is again returned, after a group of poles have been treated. This may be accomplished by a pump and piping of any suitable construction and arrangement and in the present instance comprises a pump 11 which has its inlet 12 connected by means of branch pipes 13, 14 with a main pipe 23 leading to the lower part of the impregnating tank, while its outlet 16 is connected by 100

- means of branch pipes 17, 18 with the creosote reservoir and the main pipe 23, these several branch pipes being provided with valves 19, 20, 21, 22, so that the pump may be utilized either for delivering liquid creosote from this reservoir to the creosote impregnating tank or the surplus creosote may be returned from this impregnating tank or the surplus creosote may be returned from this impregnating tank to the supply reservoir 10, by properly manipulating the valves arranged in the piping which connects this pump with the reservoir and impregnating tank.
- 15 Inasmuch as only the butt ends of the poles need to be heavily treated with creosote the lower end of the creosote impregnating tank is only filled to such a height as it is desired to protect the butt ends of the poles, a height of approximately five feet being sufficient for this purpose. A pressure gage 24 is preferably connected by means of a pipe with the interior of the creosote impregnating tank at a point adjacent to the level of the creosote, and a safety valve 25 is preferably connected with the upper part of the creosote impregnating tank, thereby enabling the operator to note the pressure within the tank and also to permit any excess pressure to escape therefrom so that the operation of the apparatus may be conducted without endangering the workmen.
- 35 The creosote in the lower part of the creosote impregnating tank may be heated so as to preserve the same in a highly fluid condition and also cause the same to penetrate the wooden poles to the maximum extent, which heating may be accomplished in various ways, for instance, by means of a pipe coil 26 arranged in the lower part of the impregnating tank adjacent to the wall thereof and around the space which is occupied by the lower or butt ends of the posts, which coil may receive any suitable heating agent, such as hot water, steam or the like. This heating agent may be supplied from any suitable source and the admission of the same to the coil may be controlled by means of a hand valve 27. If desired, the creosote vapors rising from the heated liquid creosote into the upper part of the impregnating chamber may operate either alone on the top portions of the poles or the same may be additionally heated by steam which is supplied thereto by means of a pipe 28 entering the impregnating chamber at a short distance above the normal creosote level and provided with a valve 92 for controlling the same.
- 60 At certain times in the operation of this apparatus it is desirable to produce a pressure in the impregnating tank in addition to any pressure which may be caused therein by the heat of the coil 26 and the heat of the steam supplied by the pipe 28 for the purpose of forcing the liquid creosote into the pores or interstices of the butt ends or lower portions thereof. At other times a vacuum is created within the impregnating chamber for the purpose of withdrawing the excess or surplus creosote from the butt ends of poles and thus permit of saving the excess material and utilizing it for the treatment of other poles. Although various means may be employed for thus creating a pressure within the impregnating chamber or tank and also producing a vacuum therein, the means illustrated in the drawings are suitable for this purpose and as there shown the same comprise a pump 29 having its inlet 30 connected with the atmosphere by means of a pipe 31 containing a valve 32 and its outlet 33 connected by means of a main pipe 34 having a valve 15 with the upper part of the impregnating chamber so that upon operating this pump, the air from the exterior atmosphere may be forced into the upper part of the creosote impregnating tank, whereby the liquid creosote in the lower part of this tank is forced into the pores or interstices of the butt ends of the posts and the vapors in the upper part of this tank are forced into the top portions of the poles.
- 65 The pump 29 may also be used for producing a vacuum in the creosote impregnating chamber for which purpose the main pipe 34 may be connected with the inlet of the pump by means of a branch pipe 43 containing a valve 44 and the outlet of the pump may be connected with a branch delivery pipe 45 containing a valve 46 for controlling the same. Between the main pipe 34 and the outlet pipe 33 is a valve 70 for controlling the same, as will presently appear. This branch delivery pipe may lead directly to the atmosphere, if only air or vapors of no particular value are withdrawn from the impregnating chamber when drawing the vacuum therein. If, however, the vapors are valuable, as they would be when consisting solely of creosote vapors, then the vapors discharged by the branch delivery pipe 45 are conducted by the latter into a condenser whereby these vapors are recovered and thus permits of utilizing the same to advantage for impregnating other poles. While this condenser may be of any approved type, that shown in the drawings is typical of one suitable for this purpose, and consists of a condensing vat or chamber 47 adapted to be supplied at its lower end with water by means of a supply pipe 48 containing a valve 49 while the warmed water is discharged from the upper end of this tank through an overflow pipe 50 and a coil 51 arranged in the interior of this chamber and having its upper end connected with the branch delivery pipe of the pump 45 while its lower end is connected with the upper end

of the creosote supply reservoir 10. By this means the creosote vapors which are withdrawn from the impregnating tank are delivered to the condenser where they are reduced to liquid form and then returned to the supply reservoir in condition to be used over again on poles which are subsequently treated.

Instead of treating the tops or upper portions of the poles with vapor creosote which is expensive, these parts of the poles may be treated with a protective material which is less efficient than creosote, but adequate for this part of the poles on account of the reduced destructive effect of the elements on the same. Impregnating agents having such reduced preservative capacity are usually also less expensive and thereby reduce the cost of treating the pole in its entirety. A suitable preservative material for thus treating the tops of poles at reduced cost consists of a five percent solution of zinc chloride. A supply of this zinc-chloride solution is stored in a reservoir 52 from which the same may be withdrawn and delivered into the zinc-chloride impregnating tank 100 preferably at the lower end thereof and also withdrawn therefrom by means of a pump 53 having its inlet 54 connected with the lower end of the zinc-chloride reservoir by means of a pipe 55 containing a valve 56 and with the bottom of the zinc-chloride impregnating tank by means of a by pass pipe 58 containing a valve 57, a branch pipe 59 leading to the bottom of the impregnating tank and containing a valve 68, and the outlet 64 of the pump 53 being connected with the lower end of the zinc-chloride reservoir by means of a pipe 65 containing a valve 66 and also connected with the by-pass pipe 58 and the branch pipe 59 by means of a pipe 67 containing a valve 68.

The interior of the zinc-chloride tank and its contents may be heated by a coil 61 in the lower part thereof, which coil is provided with a valve 62 for controlling the admission of the heating agent thereto, such as steam or hot water. If desired, steam may be admitted directly into the zinc-chloride tank through a pipe 35 containing a controlling valve 36. The lower end of the zinc-chloride tank may also be connected with a pressure gage 37 and the upper part of the same may be connected with a safety valve 38.

Any suitable form of gage may be employed in connection with the impregnating tanks to indicate the amount of material which is admitted to the same and the amount which is withdrawn therefrom.

A pressure may be produced in the zinc-chloride tank by the pump 29 through the medium of a pipe 39 containing a controlling valve 40 and connecting the zinc-chloride tank with the pipe 34.

Assuming that the wooden poles are to receive a liquid creosote treatment at the butt ends and a liquid zinc-chloride treatment at the tops thereof, the method of procedure would be as follows:

The group of poles 2 to be treated may be first placed in an upright position within the vertical creosote impregnating chamber or tank and the cover secured over the top of the same, so that this chamber is hermetically sealed. A batch of liquid creosote is then delivered by the pump 11 from the creosote reservoir 10 into the lower end of this impregnating tank, so as to fill the latter to a depth of about five feet, although this height may be varied to suit different requirements. Such delivery of the creosote from the reservoir to the impregnating tank may be effected by operating the pump 11 while the valves 20, 22 are open and the valves 19, 21 are closed. It would, of course, be possible to place the charge of creosote in the impregnating tank before the poles are placed therein, but it is preferable to deliver the creosote into the impregnating tank after the poles have been sealed therein, inasmuch as this reduces the loss of vapors and it is also more agreeable to the workmen. After the creosote has been thus delivered to the impregnating tank, this creosote may be heated by introducing steam into the coil 26 which causes the liquid to enter more readily into the pores or interstices at the lower or butt ends of the poles, and also causes some of the creosote to be converted into vapor, which rises and envelopes the tops or those portions of the poles arranged above the level of the liquid creosote. If only a mild or light application of creosote to the poles is required, the same are now finished so far as this step of the method is concerned and may be removed therefrom, after the liquid creosote and vapors have been withdrawn from the impregnating tank. Such withdrawal of the liquid creosote is effected by operating the pump 11 while the valves 20, 22 are closed and the valves 19, 21 open, thereby causing the creosote withdrawn from the impregnating tank to be discharged into the creosote reservoir 10. Thereafter the vapors within the impregnating tank are withdrawn therefrom by operating the pump 29 while the valves 32, 40, 70 are closed and the valves 15, 44, 46 are open, said vapors being conducted to the condenser which converts them into liquid and returns the same to the creosote reservoir. The pump 29 is preferably operated so that upon withdrawing the vapors from the impregnating tank a vacuum will be produced in the latter and thus withdraw from the pores of the poles any excess creosote or preservative which may be present therein, thereby enabling this excess material to be saved and to be used for treating other poles.

When, however, a deep penetration of the creosote into the pores or interstices of the butt ends of the poles is desired, an internal pressure is established within the creosote 5 impregnating tank so as to drive the liquid creosote into the pores of the butt ends of the poles, which pressure may also be utilized to force the creosote vapors into the tops or upper portions of the poles and increase the preservative effect on the same. Upon operating the pump 29 while the valves 32, 70 are open and the valves 15, 40, 44, 46 are closed, external air will be forced into the upper part of the impregnating tank 15 which will cause the creosote vapors therein to be driven into the tops of the poles and the liquid creosote to be forced into the lower or butt ends of the poles, the degree of penetration of the vapors and liquid being governed by the degree of pressure which is thus produced within the impregnating tank. After the poles have been thus treated heavily by strong liquid creosote at the butt ends thereof and lightly by means of weak 25 creosote vapors at the top ends thereof, the surplus liquid creosote may be again withdrawn from the lower end of the impregnating tank and the creosote vapors may be also withdrawn and condensed preparatory 30 to being returned to the creosote reservoir, in the manner previously indicated. After thus treating the butts and tops of the poles either with or without internal pressure and removing the preservative agents from the 35 impregnating tank, the cover of the latter may be opened and the group of poles removed therefrom, preparatory to introducing another group of poles when the operations described are repeated.

40 During these operations, the pressure which is produced within the impregnating chamber may be carefully noted on the pressure gage 24 so that the desired degree of penetration is obtained in accordance with 45 the character of the wood under treatment or other conditions. This pressure, however, can not exceed a predetermined limit, by reason of the employment of a safety valve 25 which will open when the pressure rises 50 to a certain point and thus render the apparatus safe in operation.

If desired, steam may be introduced into the upper part of the impregnating chamber by opening the valve 92 for the purpose of 55 heating the vapors therein and causing the same to penetrate more deeply into the tops of the poles.

Instead of treating the poles with a preservative consisting solely of creosote in liquid and vapor form, the upper ends or tops 60 of the poles may be impregnated with a liquid preservative which is less expensive, but still sufficiently effective for all practical purposes, such for instance as a zinc-chloride solution, which is stored in the 65

reservoir 52. When treating poles in this manner, the poles after being impregnated at the butt ends with liquid creosote and removed from the tank 1 are reversed or turned end for end and placed in an upright position in the zinc-chloride tank, the lid of the latter being closed to hermetically seal this tank. Then the pump 53 is operated while the valves 56, 68 are opened and the valves 57, 66 are closed, whereby the zinc-chloride solution is withdrawn from the reservoir 52 and discharged into the zinc-chloride impregnating reservoir and discharged into the zinc-chloride impregnating tank 100 to a sufficient depth so that the tops of the poles which are now lowermost, are submerged.

If desired, a pressure may be produced in the zinc-chloride impregnating tank while the poles are submerged in zinc-chloride and thereby cause the liquid to penetrate the required extent into the wood of these poles depending upon the amount of pressure which is maintained. This pressure may be produced by operating the pump 29 so as to take air from the external atmosphere and force the same into the upper part of the impregnating tank 100 while the valves 32, 40, 70 are open and the remaining valves associated with this pump closed. If desired, the zinc-chloride may be heated to facilitate the entrance of the same into the pores of the poles by opening the valves 62 of the steam coil 61.

After the poles have been thus treated with zinc-chloride, the chloride of zinc pump 53 is started, while the valves 57, 66 are open and the valves 68, 56 are closed, whereby the zinc-chloride is withdrawn from the zinc-chloride impregnating tank 100 and discharged into the reservoir 52. After the surplus zinc-chloride has been thus withdrawn from the tank 100 the lid of the latter may be opened and the completely impregnated poles may be removed and dried 110 preparatory to putting the same to their intended use.

If desired this method of treating the poles may be effected in a reverse order from that described, namely, the tops of the poles 115 may be first treated with zinc chloride solution in the tank 100, then turned end for end and placed in a reverse position in the creosote tank for treating the butt ends of the same.

For convenience in handling the poles in groups or bundles, a plurality of the same may be placed in a crate or holder 71, as shown in Fig. 2, which crate containing a load of poles or the like can be readily lowered into and raised out of the tanks by a crane or derrick and thus expedite this work.

Treatment of poles or the like with creosote and zinc-chloride at the opposite ends 120

of the same in accordance with the above described method can be effected thoroughly and economically, inasmuch as the amount of preserving material entering the pores of the poles is positively under control and the surplus from each group of poles is recovered and used for treating succeeding groups. Not only is a considerable saving in material effected but also in time of completing the treatment and drying the poles since this process permits of accomplishing this work much more expeditiously than the methods heretofore used.

Instead of arranging the impregnating tanks in a perfectly vertical position as shown in the drawings the same may be inclined more or less, but for all practical purposes the same should not be inclined more than about forty-five degrees to the horizontal, as shown at 200 in Fig. 3, and such an inclination is regarded as substantially upright for the purpose of practicing this invention.

If desired the purpose of this invention may be attained by first placing the poles in one of the tanks or retorts, then filling the tank with creosote or other preservative material, so as to cover the entire surface of the poles, then withdrawing some of the preserving material so as to submerge the poles only partly, say a distance of four to six feet from the lower ends of the same, and then applying air pressure to the interior of the tank, whereby the thin coating adhering to the upper part of the poles will be driven into the poles and furnish moder-

ate protection and a maximum amount of preserving material in the lower part of the tank will be forced deeply into the lower part of the poles for increasing the resistance of the same to decay. 40

I claim as my invention:

The herein-described method of treating opposite ends of a wooden pole with preservatives having different degrees of decay resisting properties, which method consists in first placing the entire pole in a vertical position within a tank containing in its lower part a liquid preservative of one strength so that only the lower end of the pole is submerged in said liquid while its upper end is above the liquid level, applying a certain degree of air pressure to the interior of said tank which drives the liquid preservative into the lower part of the pole and simultaneously subjecting the unsubmerged upper part of the pole to the same air pressure, then reversing the pole end for end and placing the entire pole in this reversed position into a tank which contains a liquid preservative of a different strength in which the last mentioned lower part of the pole is submerged while the last mentioned upper part thereof is unsubmerged, and then applying a different degree of air pressure to the interior of the tank whereby the mass of preserving liquid is driven into the last mentioned lower part of the pole and the coating of preserving liquid is driven into the last mentioned unsubmerged part of the pole. 60 65 70
